UNITED STATES PATENT OFFICE.

THOMAS C. HARVEY, OF SAN FRANCISCO, CALIFORNIA.

HEADLIGHT-DIMMER.

1,205,093.

Specification of Letters Patent.

Patented Nov. 14, 1916.

Application filed February 29, 1916. Serial No. 81,267.

To all whom it may concern:

Be it known that I, THOMAS C. HARVEY, a citizen of the United States, residing in the city and county of San Francisco and 5 State of California, have invented a new and useful Improvement in Headlight-Dimmers, of which the following is a specification.

My invention relates to socalled dimmers 10 for vehicle headlight wherein inclined bars operate in conjunction with the reflector of the headlight; and the objects of my invention are: First, to provide improved means whereby a portion of the magnified light rays 15 are deflected toward the ground on both sides of the headlight. Second, to provide improved means adapted to partially screen the lower portion of the headlight. Third, to provide improved means arranged to deflect a portion of the magnified light rays to 20 one side of the headlight. I accomplish these several objects by means of the device disclosed in the drawings forming a part of the present specification wherein like characters 25 of reference are used to designate similar parts throughout the said specification and drawings, and in which—

Figure 1 is a rear elevation of my improved dimmer disclosing the arrangement 30 of the arcuate and central bars. Fig. 2 is a vertical longitudinal sectional view of a headlight reflector disclosing my improved device in section, secured thereto. Fig. 3 is a horizontal section of the reflector and 35 dimmer disclosing the manner in which the central bar deflects a portion of the magnified rays to one side of the headlight.

Referring to the drawings the numeral 1 is used to designate a reflector of the parabolic type having the usual lamp 2 slidably mounted within a suitable socket 3. A metal ring 4 is adapted to be secured within the front of the headlight and is provided with an annular flange 6. A series of inclined arcuate bars 7 are secured across the lower portion of the ring 4 and have their ends soldered or otherwise secured in the angle formed by the junction of the flange 6 with the ring 4. The inclined arcuate bars 50 7 are arranged to partially screen the lower portion of the headlight or reflector 1 when the ring 4 is in position in order to eliminate the blinding glare visible to a person in front of the light when the eyes of said 55 person are slightly above said headlight.

The arcuate bars 7, by reason of the inclined curved under surface thereof, will also tend to diffuse the light by deflecting a portion of the magnified rays toward the ground and on either side of the headlight as disclosed by the broken lines in Fig. 1 of the drawings. A vertically disposed central bar 8 is secured to the arcuate bars 7 and to the junction of the flange 6 with the ring 4. The central bar 8 is inclined or set at an angle 65 in a vertical plane so that a portion of the magnified rays from the headlight or reflector 1 will be deflected toward one side of the vehicle headlight thus enabling the driver of the vehicle to discern objects at 70 the side as well as in front of him.

It is intended that dimmers of this type shall be made with the central bars 8 inclined in opposite directions so that the light will be deflected toward both sides of 75 the road.

It is obvious from the foregoing that I have provided an improved dimmer for vehicle headlights that is adapted to screen the glare of the lower portion of the reflector or headlight and also to deflect a portion of the light rays to both sides of the vehicle as well as toward the ground. 80

Having thus described my invention what I claim as new and desire to secure by Letters Patent is—

1. A dimmer for vehicle headlights comprising a series of arcuate inclined bars arranged to deflect the magnified light rays toward the ground; and means for deflecting a portion of the magnified rays to one side. 90

2. A dimmer for vehicle headlights comprising a series of arcuate inclined bars arranged to partially screen the lower portion of the headlight and to deflect a portion of the magnified light rays toward the ground; means arranged to deflect a portion of the rays to one side of the headlight; and means secured to the arcuate bars and side deflecting means and arranged to secure the same to a headlight. 95

3. A dimmer for vehicle headlights comprising a series of arcuate inclined bars arranged to partially screen the lower portion of the headlight and to deflect a portion of the magnified light rays toward the ground; means arranged to deflect a portion of the magnified light rays to one side of the headlight; and a suitable ring secured 100

105

110

to the arcuate bars and to the side deflecting means whereby the same may be secured within a headlight.

4. A dimmer for vehicle headlights comprising a series of inclined arcuate bars arranged to partially screen the lower portion of the headlight and to deflect a portion of the magnified light rays toward the ground; a vertically disposed central bar arranged to deflect a portion of the light rays to one side of the headlight; and a suitable ring secured to the arcuate bars and to the vertical bar whereby the same may be secured within a headlight.
5. A dimmer for vehicle headlights com-

prising a series of inclined arcuate bars arranged to partially screen the lower portion of the headlight and to deflect a portion of the magnified light rays toward the ground; a central vertically disposed bar 20 secured to the arcuate bars and inclined in a vertical plane so as to deflect a portion of the magnified light rays to one side of the headlight; and a suitable ring secured to the arcuate and central bars whereby the 25 same may be secured within a headlight.

In witness whereof I hereunto set my signature.

THOMAS C. HARVEY.
